SLICING MACHINE

Wilhelmus Adrianus van Berkel, Clarens, Montreux, Switzerland, assignor to U. S. Slicing Machine Company, La Porte, Ind., a corporation of Indiana

Application December 12, 1931, Serial No. 580,560
In Great Britain September 5, 1931

7 Claims. (Cl. 146—102)

This invention relates in general to slicing machines in which the holder for the substance to be sliced is slidably mounted upon an under-table. More particularly, the invention relates to means for slidably moving the feed table relative to the base of the machine.

It is known, in connection with slicing machines, to provide the substance holder with certain mechanism capable in itself of guiding the holder in its movement across the under-table toward and away from the slicing knife. Such mechanism has been termed "narrow guide mechanism" and is substantially disposed at one side of the substance holder. This narrow guide mechanism also functions normally to impose a frictional drag on the substance holder to insure the cutting of slices each of which will have precisely the same desired thickness.

The primary object of the invention is to provide new and improved guiding mechanism for slidably mounting the substance holder relative to the base of the machine.

Another object of the invention is to provide new and improved means for detachably securing a substance holder to slidable guide means which guide means are arranged in a narrow guideway from which the guide means are rendered removable by the act of detaching and removing the substance holder.

Another object of the invention is to provide improved means for detachably securing slidable guide means to a substance holder, said means being arranged between rigid walls of a narrow guideway.

A further object is to provide means comprising a main member and an auxiliary member both normally spring pressed against the side walls for rendering a slicing machine substance holder detachable and slidable and also for the purpose of creating a frictional drag on the substance holder.

A still further object is to provide a slicing machine which has a substance holder movable in a predetermined direction by a feed screw, which has a relatively narrow guideway mounted in the base thereof, the guideway carrying spaced blocks, which has means for tilting the blocks in a predetermined position to create a frictional drag on the substance holder, and which has means for disconnecting the substance holder from the feed screw and releasing the frictional drag whereby the substance holder may be made to slide freely and easily along a base.

Still another object is to provide means including horizontally arranged springs which are

interposed immediately between slide blocks and which are adapted normally to press the blocks into contact with the walls of a narrow guideway.

Numerous other objects and advantages will be apparent throughout the progress of the following specification.

The accompanying drawings illustrate a selected embodiment of the invention and the views therein are as follows:

Fig. 1 is a detail elevation of a slicing machine and embodying the invention.

Fig. 2 is a detail plan view of the improved slicing machine.

Fig. 3 is a detail plan section on the line 3—3 of Fig. 1.

Fig. 4 is a detail sectional view on the line 4—4 of Fig. 3 showing the parts in normal operating position.

Fig. 5 is a detail sectional view on the line 5—5 of Fig. 3.

Fig. 6 is a view similar to Fig. 4 showing the parts out of their normal operating position.

Fig. 7 is a detail sectional view on the line 7—7 of Fig. 3.

The slicing machine herein shown has an under-table 10 above which there is mounted a substance holder 11. Automatic feed mechanism (not shown) is provided for imparting step-by-step movement to the substance holder 11 through the intermediary of an intermittently rotatable screw feed 12. A feed nut 13 connected to the substance holder 11 has meshing relation with the feed screw 12.

Narrow guide mechanism consisting of a narrow guideway and slidable means in the guideway is provided for rendering the feed table freely slidable when desired. The narrow guideway consists of a channel section portion and comprises a base 14 and oppositely disposed side walls 15 and 16. Slidable guide means comprising a main member or slide block 17 and an auxiliary or retaining member 18 are slidably arranged in the narrow guideway which guideway is defined by the walls 15 and 16 and the base 14. The slide block 17 and the retaining member 18 are associated with a thin plate 19 which is secured to the guide block 17 and is disposed between the under-table 10 and the substance holder 11. The plate 19 has a plurality of pivot pins 20 forming suspensory connections with the retaining member 18. A plurality of horizontally arranged springs 21 are arranged in oppositely disposed recesses 22 and 23 formed in the guide block 17 and the retaining member 18 respectively. A

tongue 24, Figs. 4 and 6, is secured to the retaining member and projects out of the narrow guideway, making contact with a wiper 25 on a cam 26. The cam 26 is pinned to a manually 5 turnable shaft 27 which is journalled at its ends in a casing 28, and which is provided with a handle 29 at one end. The wiper 25 has a projection which cooperates with the tip of the tongue 24. The handle 29 is associated with a handle 30 10 which is fixed to an extension of the casing 28. The casing 28 is connected by screws 28', Fig. 3, to the slide or guide block 17.

The cam 26 bears against the top end of a lever 31, Figs. 4 and 6, whose lower end carries the 15 segmental feed nut 13. The lever 31 is pressed against the cam 26 by a spring 32 which is anchored in a semi-spherical casing 33. The semi-spherical casing 33 is secured to the casing 28 and supports the fulcrum 34 of the lever 31.

20 The normal or operating position of the retaining member 18 is that shown in Fig. 4 which position is the result of the springs 21 acting thereagainst and also the action of the wiper 25 on the tongue 24. As shown, one of the bottom corners 25 of the member 18 presses into the wall 16 of the narrow guideway, thereby causing the member, when in tilted position, to impose a drag or frictional resistance to the movement along the narrow guideway of the slide block 17. When the 30 member 18 is in tilted position it also acts to prevent the slide block 17 from being inadvertently lifted out of the narrow guideway.

The slide or guide block 17 and the retaining member 18 cannot be removed from the narrow 35 guideway when the substance S to be sliced, Figs. 1 and 2, is being tightly clamped upon the substance holder 11 by pressing down forcibly on the usual clamp which is supported by the uprights 35 and 36, Fig. 3. The uprights 35 and 36 40 are mounted on a raised part 37 of the substance holder 11. The plate 19 is extended across the top of the guideway and enters a recess between the wall 16 and an angle bar 38 which is secured to the wall, Figs. 2 to 7 inclusive. When 45 pressure is applied to the clamp, the plate 19 presses upwardly against the top of the angle bar 38 and prevents upward movement of the slide block 17 and the other parts associated with the plate.

50 In order to render the retaining member 18 inoperative it is simply necessary to grasp the handles 29 and 30 at which time the handle 29 will turn, causing the shaft 27 to partially rotate and turn the lever 31 in a counterclockwise direction.

55 When the shaft 27 is partially rotated, the parts will be in the position shown in Fig. 6 and the feed nut 13 will be out of engagement with the said screw 12. At the same time the wiper 25 will 60 depress the tongue 24 and cause the member 18 to tilt in a counterclockwise direction about its suspensory pivotal connections 20. The operation of the handle 29, partially rotating the shaft 27, causes the biting action of the retaining member 18 on the wall 16 of the narrow guideway to be relieved. The slide block 17 can then be pushed or pulled along the guideway without any restraint. Also, the members 17 and 18 may be removed from the narrow guideway by lifting 65 the substance holder 11 after the removal of the bar 38.

In order that the substance holder 11 can be 70 accurately located on the slide block 17, the slide block is provided with two upstanding projecting tapered pins 39, Fig. 7. These pins 39 are

engaged by correspondingly tapered holes in the raised part 37 of the substance holder. The substance holder is thus properly located and is locked in position by means of a latch 40, Figs. 3 and 5, which is pivotally attached by a pin 41 10 to the part 37 of the substance holder. A handle 42 is provided on the latch 40 for turning the latch. The latch 40 cooperates with a pin 43. The pin 43 is secured to the slide block 17 by means of a screw 44, Fig. 5, and is formed with a recess 45, Fig. 3, into which the latch 40 enters when the handle 42 is appropriately turned. The latch has an inclined top surface (as shown) particularly in Fig. 5 and cooperates with the recess 45 which is properly shaped to receive the latch. 15 The shaping of the latch and the recess insures tight engagement between the substance holder and the guide block.

In order to remove the substance holder from the machine it is simply necessary to turn the 20 handle 42 clockwise, Fig. 3, after which time the substance holder can be raised clear of the machine.

When the handles 29 and 30 are grasped and the shaft 27 turned so as to cause the retaining 25 member 18 to occupy its inoperative position, as shown in Fig. 6, the simple act of unlocking and removing the substance holder leaves the slide block 17, the retaining member 18, and the plate 19 free to be at once removed from the narrow 30 guideway provided, of course, the angle 38 has been removed. The removal of these parts permits them to be readily inspected, cleaned, repaired, or replaced.

The invention provides new and improved 35 guide means for a substance holder of slicing machines. The retaining member has a pivotal connection with a plate which is slidably mounted between the guideway and the substance holder. The plate enters a recess which is associated with 40 the narrow guideway and is adapted to prevent the slide guideway from being forcibly removed therefrom when clamping pressure is applied to the substance holder. The device is positive and efficient in operation permitting the 45 substance holder to have freely slideable movement when required and allowing the parts to be readily removed for the purpose of cleaning, replacing, and repairing.

Changes may be made in the form, construction, 50 and arrangement of the parts without departing from the spirit of the invention or sacrificing any of its advantages, and the right is hereby reserved to make all such changes as fairly fall within the scope of the following claims.

55 The invention is hereby claimed as follows:

1. A slicing machine comprising a base, said base having a guideway formed therein defined by side walls, slide guide means arranged between the walls of the guideway, said slide means comprising a main member and an auxiliary member, horizontally arranged springs interposed between said members and pressing said members into contact with the side walls, means for moving one of said members angularly to cause frictional engagement of said members in the guideway, said guideway being provided with a recess, a substance holder, a plate arranged between the substance holder and the base and engaging said recess, and means for fastening said plate to the slideable means.

2. A slicing machine comprising a base having a guideway formed therein, a slide member arranged in said guideway, a second slide member arranged in said guideway, a substance 75

- holder carried by said base, a plate under the substance holder, means connecting the first member to the plate, and means pivotally connecting the second member to the plate.
- 5 3. A slicing machine comprising a base having a guideway formed therein, a slidable member arranged in said guideway, a second slidable member arranged in said guideway, a substance holder carried by said base, a plate under the substance holder, means connecting the first member to the plate, means pivotally connecting the second member to the plate, and pivoted means for tilting the second member to create a drag with the guideway.
- 10 4. A slicing machine comprising a base having a guideway formed therein, a slidable member arranged in said guideway, a second slidable member arranged in said guideway, a substance holder carried by said base, a plate under the substance holder, means connecting the first member to the plate, means pivotally connecting the second member to the plate, pivoted means for tilting the second member to create a drag with the guideway, a slot and pin connection between the substance holder and the first member, and clamping means for clamping the substance holder in rigid position relative to the first named member.
- 15 5. A slicing machine comprising a base having a guideway formed therein, a pair of slidable members arranged in the guideway, a substance holder supported by the base, a plate over the guideway and beneath the said holder, one of said slidable members being connected to the plate, and a pivoted connection between the plate and other member.
- 20 6. A slicing machine comprising a base having a guideway formed therein, a pair of slidable members arranged in the guideway, a substance holder supported by the base, a plate over the guideway and beneath the said holder, one of said slidable members being connected to the plate, a pivoted connection between the plate and other member, feed controlling means cooperating with one of said members to tilt the same and create a friction against a wall of the guideway, and means for clamping the substance holder, the plate and one of said members together.
- 25 7. A slicing machine comprising a base and a substance holder, said base having a guideway formed therein defined by side walls, slidable guide means arranged between the walls of the guideway, said slidable means comprising a main member and an auxiliary member, horizontally arranged springs interposed between said members and pressing said members apart and into engagement with the side walls of the guideway, a plate situated between the base and the substance holder, and means pivotally connecting one of said above members to said plate for moving said one member angularly into and out of frictional engagement with a wall of the guideway.
- 30 WILHELMUS ADRIANUS VAN BERKEL.
